atty.

UNITED STATES PATENT OFFICE.

ADOLPHE POUMAY, OF JAMBES-LEZ-NAMUR, BELGIUM.

CUPOLA FURNACE.

Application filed April 16, 1923, Serial No. 33,637, and in Belgium April 18, 1924.

My invention relates to cupola furnaces and has for its object a construction whereby the consumption of fuel is reduced as compared with such furnaces as hitherto 5 constructed.

Another object of my invention is to obtain, in such a cupola furnace, that the carbon monoxide which is produced in the melting zone may be used for the production 10 of a combustible mixture which may then be burnt at a distance above the melting zone whereby the heat resulting from this combustion is used for the preliminary heating of the charges.

With these objects in view, my invention 15 essentially consists in a special arrangement and combination of sets of tuyères for the air blast as will be hereinafter fully described and pointed out in the appended 20 claims.

Referring to the annexed drawing:

Fig. 1 is an elevation of a cupola furnace constructed according to my invention.

Figs. 2-3 and 4 are, respectively half sections on the lines 2-2, 3-3 and 4-4 in Fig. 1.

The cupola is constructed in the usual 30 way of a barrel like body 1 of riveted sheet metal having the refractory lining 2 and provided with a circular air chamber 3 which supplies the blast to all the tuyères at different levels, 4 being the inlet thereto.

According to my invention it is made use 35 of three sets of tuyères 5, 6 and 9.

The lower set of tuyères 5 for melting are made as small as possible in the height of their cross-section in order to obtain a melting zone of reduced thickness to avoid the oxidation of the various bodies in the metal 40 being treated.

As a consequence of the action of the said tuyère 5 there is a large production of carbon monoxide in this zone of the cupola.

The second set of tuyères 6 is arranged 45 at a higher level and at the upper part of the melting zone. These tuyères 6 are of a much smaller cross-section than the tuyères 5 and each formed with branches (see Fig. 2) 7 and 8, the branch 7 being directed towards the centre of the cupola whilst the branch 8 is tangential thereto, whereby a gyroscopic movement is imparted to the air jets assuring a vigorous mixing thereof with the gas ascending in the cupola. 50 The third set of tuyères 9 comprises a number of tuyères which may be called "the regenerative tuyères" and which are arranged in the part of the cupola containing the charge; the said tuyères which are branched on the circular air chamber 3 by 60 pipes 10 are arranged at different heights so as to feed the air into the cupola, at different levels in the charges. In this part, the temperature being little raised and the coke red hot, the ascending gases are burnt 65 under the supply of air, thus preparing the charges which they meet for a rapid melting in the zone fed by the tuyères 5. All the tuyères are provided with regulators 11 or cocks 12 in order to allow of regulating the 70 admission of air necessary for the correct working of the cupola. The number and cross-section of the different tuyères must, of course, be proportional to the calculated output of the apparatus. 75

With regard to the special operation of the arrangement thus described, the following is to be noted:

The gases which are produced in a cupola tend always to ascend in the said cupola 80 without reaching the centre of the charge in the melting zone. The tuyères 5 and 6 are preferably slightly inclined downwardly so as to retain the gases in the said zone and to secure the proper action of the blast 85 on the whole sectional area of the cupola, thus producing a great number of calories in the time unit. In fact at the level of the tuyères 5, the combustion takes place with production of carbon dioxide but this carbon dioxide on passing through the ignited coke, between the tuyères 5 and the tuyères 6 is converted into 2 CO. At the level of the tuyères 6 a similar operation takes place, on account of the air which is fed by the 90 said tuyères. But at this level, the ascending gases on meeting the air which is fed diametrically by the branches 7 of the tuyères 6, are compelled to follow the direction of the air 95 and are thus directed towards the centre of the cupola. Further, the air which is injected tangentially through the branches 8, gives to the said gases a gyroscopic movement preventing the direct ascension of the gases. Further owing to the proportion of air 100 which is injected at the level of the tuyère 6, a mixture of air and carbon monoxide is formed. This mixture is then burnt and the carbon monoxide is gradually converted in carbon dioxide at the different levels of 105 the regenerative tuyères 9. The heat which is thus produced prepares the charges in 110

such a manner that when the said charges reach the melting zone, they can be melted with a reduced quantity of heat.

What I claim is:

- 5 1. In a cupola furnace, in combination with an air chamber surrounding the furnace at the level of the melting zone, a lower set of tuyères arranged towards the centre of the furnace, a second set of tuyères arranged at a higher level, the said tuyères comprising two branches, one of which is directed towards the center of the furnace and the other tangentially thereto and a third set of tuyères spirally arranged around the 15 cupola whereby air is fed by the tuyères of the third set at relatively different levels throughout a furnace area from the air chamber to that part of the furnace containing the charge.
- 20 2. In a cupola furnace, a barrel-like body,

an upper part of the said body containing the charges to be treated and a lower part forming a melting zone, an air chamber surrounding the furnace at the level of the said melting zone, a lower set of downwardly inclined tuyères arranged towards the centre of the furnace, a second set of downwardly inclined tuyères arranged at a higher level, the said tuyères comprising two branches one of which is directed towards the centre of the furnace and the other tangentially thereto and a third set of tuyères spirally arranged around the cupola whereby air is fed by the tuyères of the third set at relatively different levels throughout a furnace area from the air chamber to that part of the furnace containing the charge.

In testimony whereof I have affixed my signature.

ADOLPHE POUMAY.
